UNITED STATES PATENT OFFICE.

JAMES BOLTON AND HENRY DEFORGE, OF FITCHBURG, MASSACHUSETTS.

SHUTTLE ATTACHMENT.

1,237,236.

Specification of Letters Patent. Patented Aug. 14, 1917.

Application filed January 18, 1917. Serial No. 143,159.

To all whom it may concern:

Be it known that we, JAMES BOLTON and HENRY DEFORGE, citizens of the United States, residing at Fitchburg, in the county 5 of Worcester and State of Massachusetts, have invented a new and useful Shuttle Attachment, of which the following is a specification.

This invention relates to an attachment 10 for the spindle of a shuttle, and the principal objects thereof are to provide a removable attachment suited for holding a bobbin centrally and firmly in position on a cop spindle; to provide said attachment in such form 15 as to accomplish this purpose simply and efficiently; and to provide readily detachable means for securing the attachment to the spindle. Further objects and advantages of the invention will appear herein- 20 after.

Reference is to be had to the accompanying drawings in which—

Figure 1 is a side view of a shuttle with a preferred form of this invention applied to 25 the spindle thereof, showing the spindle in its outermost position and the bobbin in section;

Fig. 2 is a side view of the shuttle spindle;

Fig. 3 is a similar view of the attachment, 30 and

Fig. 4 is a plan of the attachment looking in the direction of the arrow 3 in Fig. 2.

This invention is designed to be applied to a shuttle 10 of ordinary type having a 35 spindle 11, preferably of the spring type designed to hold an ordinary cop. It is well known in practice that shuttles of this kind are employed for both cops and bobbins, but that the spindles, although usually slit 40 throughout the greater part of their length to provide a yielding divergence of the sides thereof, really effectively hold the cop only. When a bobbin is applied the same is held in position eccentrically and loosely. This 45 permits the bobbin to shake around loosely on the spindle and often creates bad work in the use of the device. This invention is designed to be applied especially to that kind of spindle, although capable of general use.

50 Referring further to the drawings it is to be observed that the mechanism for holding the spindle in its two extreme positions is not illustrated in detail because any desired means can be used for that purpose.

55 The spindle, however, is modified to a cer-

tain extent over the ordinary structure because it is cut out at 13 to provide a notch having a square shoulder at the upper end, the surface of the notch slanting away below it. This is the only modification of the 60 existing form of spindle and its connected parts that is required.

The attachment itself as shown here comprises a tubular member 15 having a cylindrical butt end at 16 provided with a pair 65 of integral transverse projections 17 for engaging in the notches *a* usually found in a bobbin A. The upper end of this attachment is shown as contracted at 18 to facilitate its entry into the large end of the bobbin. It is preferred to cut away the attachment about half way through the same to expose the interior passage at 19, this cut away portion extending throughout a large 70 part of the attachment. 75

This attachment can be made of sheet stock and is so shown in the drawings, the projections 17 being cut from the stock and bent outwardly, and the contraction at 18 being provided by slitting in the end, bending the tongues between the slits inwardly, and turning or grinding off the surface. 80

The tubular member 15 is further provided with a flat steel spring or holding member 20. This can be applied to it in 85 any desired way and can be made of any desired material other than steel. It is shown in the drawings as attached by providing it with a tang 21 of a general cross shape integral with it and having its transverse projections entering into notches in the cylindrical portion of the attachment formed at the ends of a pair of slits 22 provided therein. The tongue between the slits 22 is pressed down after the spring is 90 inserted. These parts can be spot-welded or otherwise secured together and a spring can be used formed of non-metallic material. 95

With this construction it will be seen that a cop can be applied to the spindle in the 100 usual way without the use of this attachment, and the shuttle used as has been the custom heretofore. But when a bobbin A is to be used the attachment is simply slipped on until the spring 20 catches into the notch 13 to hold the attachment in position. Then the bobbin is placed on it and turned until its notches *a* receive the projections 17 when it is found that the bobbin 105 is centered on the spindle, because the at- 110

tachment is substantially of the diameter of the passage through the bobbin. Different sized attachments can be used for bobbins of different construction.

5 In this way it will be seen that the bobbin cannot vibrate materially on this device, but that it is accurately centered and that consequently it will feed the yarn uniformly and without as much liability to breakage
10 as has been the case heretofore. After the bobbin is removed and it is desired to change the loom over to run cops the attachment is very readily detached from the spindle by turning it on its own axis until
15 the spring is released from the notch 13 when the attachment can be drawn off very readily. Up to that time, however, it is to be observed that the spring and notch, having straight surfaces in engagement with
20 each other, hold the tubular attachment against turning on the spindle accidentally. It is also to be seen that the large part of the bobbin will come into concentric position with relation to the usual projecting
25 plate at the bottom of the spindle.
Although we have illustrated and described only a single form of the invention and shown only one size and construction thereof we are aware of the fact that modifications can be made therein by any person skilled in the art without departing from the scope of the invention as expressed in the claims. Therefore we do not wish to be limited to all the details of construction
30 herein shown and described nor to the particular type of shuttle and spindle illus-

trated, nor to the materials mentioned, but what we do claim is:—

1. The combination with a shuttle spindle having a notch therein, of a removable attachment therefor for holding a bobbin, said attachment being provided with means for engaging in the notch to hold the attachment on the spindle, said means being adapted to be released from the spindle by 40 the turning of the attachment thereon.

2. As an article of manufacture, an attachment for a shuttle spindle of a general tubular shape adapted to fit the inside of a bobbin and provided with a spring for detachably holding it on the spindle, said spring having opposite projections and the attachment a pair of slits receiving the edges of said projections to hold the spring. 50

3. As an article of manufacture, a tubular attachment for a shuttle spindle adapted to fit the inside of a bobbin and provided with means for holding it on the spindle, and having transverse projections at its butt end for engaging in notches in the bobbin. 55

4. The combination with a shuttle spindle having a notch therein, of an attachment therefor for holding a bobbin provided with a spring for engaging in said notch to hold the attachment on the spindle, said attachment being adapted to be turned on the spindle to release the spring from the notch. 60

In testimony whereof we have hereunto affixed our signatures.

JAMES BOLTON.
HENRY DEFORGE.
